(57) **CLAIM**

The ornamental design for a cryogenic vial storage rack assembly, as shown and described.

DESCRIPTION

FIG. 1 is a front perspective view of a cryogenic vial storage rack assembly including a cryogenic vial storage rack and a cryogenic vial storage rack holder, showing our new design; FIG. 2 is a perspective view of the cryogenic vial storage rack assembly showing only the cryogenic vial storage rack of FIG. 1;

FIG. 3 is a top view thereof;

FIG. 4 is a bottom view thereof;

FIG. 5 is a perspective view of the cryogenic vial storage rack assembly showing only the cryogenic vial storage rack holder of FIG. 1;

FIG. 6 is a top view thereof;

FIG. 7 is a bottom view thereof;

FIG. 8 is a bottom view of the shelf of the cryogenic vial storage rack holder of FIG. 5;

FIG. 9 is a perspective view of the cryogenic vial storage rack assembly of FIG. 1 positioned in a controlled-rate freezer; and,

FIG. 10 is a perspective view of the cryogenic vial storage rack of FIG. 2 positioned in another storage rack holder, such as a storage rack holder for a liquid nitrogen storage container.

The dashed lines in the drawings depict portions of the cryogenic vial storage rack assembly that form no part of the claimed design. The short dash-long dash lines in the drawings depict environmental subject matter and form no part of the claimed design.

1 Claim, 10 Drawing Sheets
